UNITED STATES PATENT OFFICE.

ARNOLD KRIWAN, OF MAHRISCH-OSTRAU-PRIVOZ, CZECHOSLOVAKIA.

ROLLING MILL WITH SUPPORTED WORKING ROLLS.

Application filed December 24, 1926, Serial No. 156,937, and in Germany December 8, 1924.

This invention relates more particularly to that type of rolling-mills for the elongation of material in which the working rolls are supported. In such rolling-mills the 5 diameter of the rolls should be as small as possible, because experience has shown that rolls of small diameter produce great elongation of the material to be rolled. Said rolls of small diameter, however, show, under 10 the counter-pressure of the material to be rolled, a considerable sagging or deflection and must therefore be supported. For this purpose it has previously been proposed to adopt, either, supporting rolls extending 15 over the entire length of the working rolls and running in bearings in the housings, or supporting rails resting on the working rolls and undergoing a shifting motion while the rolls are revolving. The known 20 supporting rolls are applicable for plain working rolls only, and not for rolls having various diameters on their longitudinal extent. In addition thereto, there occur very 25 strong pressures and frictional strains in the necks of the supporting rolls, so that special cooling arrangements have to be provided.

Furthermore, rolling-mills have become known, in which the comparatively thin 30 working rolls are supported by short supporting rolls revolvably arranged on stationary shafts and distributed over the whole length of the working rolls. Said supporting rolls are secured against lateral displacement and preferably constructed as 35 roller-bearings, to ensure a reliable working.

In order to attain a better support of the 40 working rolls and to reduce the number of the supporting members, the present invention provides for each working roll a plurality of short supporting rolls, comprising each a plurality of roller-bearings revolvably mounted on a stationary shaft and a roller-shaped body enclosing the latter and 45 being in direct contact with the working roll, cavities being formed by said roller-bearings within the supporting rolls, which cavities are used as lubricating chambers. The distances between the roller-bearings 50 are secured by inwardly projecting shoulders on the roller-shaped body and by intermediary rings on said shaft respectively, while the roller-bearings are secured against outward displacement by a shoulder on said shaft and by a ball-bearing at one end of 55 said body respectively.

The accompanying drawings illustrate the improved rolling-mill in two appropriate constructional forms, namely as a twin and as a three-high rolling-mill respectively:— 60 Fig. 1 is a side view of a twin rolling-mill, Figs. 2 and 3 are respectively a longitudinal and a transverse section through the latter, Fig. 4 shows a detail of Fig. 2 on a larger scale, Fig. 5 shows the mounting of the ends 65 of the working rolls in a side view, and Fig. 6 the same in a horizontal section on the line 6—6 of Fig. 5, Fig. 7 shows the mounting of the ends of the supporting rolls in a side view, and Fig. 8 the same in a horizontal section on the line 8—8 of Fig. 7. Fig. 9 is a similar view to Fig. 3 of a three-high rolling-mill, and Fig. 10 shows part of a working roll for the latter with a bearing 70 for the same in section, on a larger scale. 75

The two working rolls *a* of the twin rolling-mill illustrated in Figs. 1 to 8 inclusive, are each supported by two pairs of supporting members *b*, *c* revolvably arranged on stationary shafts *d*, which are immovably 80 mounted in housings *e* and screw-threaded at their ends so as to be fixed at the outside of said housings by means of nuts *d*¹ (Fig. 4).

As shown in Fig. 4 on a larger scale, each 85 supporting member comprises two roller-bearings of which the inner counter-rings *f* are fitted with races for obliquely arranged rollers *g*, on which the outer counter-rings *h* are revolvably mounted. Said outer rings *h* are connected and enclosed by an outer 90 steel cylinder *i*, a cavity *k* being left between the rings to serve as a lubricating chamber. Said rings bear at their inner adjacent ends against an inwardly projecting shoulder *m* of the steel cylinder *i* and against an intermediary ring *n* on the shaft *d* respectively, while they are secured against outward displacement by a shoulder *o* on the shaft *d* and a ball-bearing *p* at one end of the cylinder *i* respectively; end discs *q*, *r*, of which the 100 latter bears from inside against the housing *e*, serving to close the steel cylinder *i* at its ends and to provide counter-bearings for the outer rings *h* and for the ball-bearing *p* respectively. The steel cylinder *i* forming 105 thus a roller-shaped body, is in direct contact with the working roll to be supported, and it is preferably provided with a slightly convex rim (Fig. 2) to prevent undue friction with the working roll when the latter is 110 under high load or pressure.

As shown in Figs. 5 and 6, the working

rolls a can be laterally withdrawn after removal of the guiding-rails s , while the housing in the opposite framing remains therein. A dismounting of the counter-bearings is not required.

As shown in Figs. 7 and 8, the housing e for the supporting roll b is held at one side by a removable rail t .

The roller-bearings mounted on the stationary shafts, as well as the supporting bearings arranged on the housings, remain always closed.

Fig. 9 illustrates a three-high rolling-mill having a fixed middle working roll a^2 and supporting rolls b^1, c^1 for the rotary working rolls a^1 , while Fig. 10 shows a bearing for a rotary working roll a^1 .

Said bearing is provided with a middle cavity u and two lateral cavities v . The latter receive each two or more metal rings w located at an angle of 49° and fitted on their outer sides and edges with a strong washer z of rubber linen on which acts a steel disc x by means of an outwardly projecting screw y . Said cavities v are filled with a lubricant, which is tightly held therein by means of the just described contrivance, while the middle cavity u serves for cooling purposes.

What I claim, is:—

30 1. The combination, in a rolling-mill, of supported working rolls, a plurality of

axially immovable short supporting rolls for each working roll distributed over substantially the whole length of the latter and comprising each a plurality of roller-bearings 35 and a roller-shaped body enclosing the latter and being in direct contact with said working rolls, lubricating cavities being formed by said roller-bearings in said supporting rolls, and a stationary shaft on 40 which said roller-bearings are revolvably mounted.

2. In a construction as specified in claim 1, an inwardly projecting shoulder on said roller-shaped body, an intermediary ring on 45 said shaft, both arranged between the adjacent inner ends of said roller-bearings, and means to secure the latter against outward displacement.

3. In a construction as specified in claim 1, 50 an inwardly projecting shoulder on said roller-shaped body, an intermediary ring on said shaft, both arranged between the adjacent inner ends of said roller-bearings, a shoulder on said shaft bearing against one 55 outer end of said roller-bearings, and a ball-bearing at one end of said roller-shaped body bearing against the other outer end of said roller-bearings.

In testimony whereof I have hereunto set 60 my hand.

ARNOLD KRIWAN.
